UNITED STATES PATENT OFFICE.

ALBERT BECK, OF CHICAGO, ILLINOIS.

DESIGN FOR A GAME-BOARD.

SPECIFICATION forming part of Design No. 28,083, dated December 21, 1897.

Application filed April 5, 1897. Serial No. 630,869. Term of patent 3½ years.

To all whom it may concern:

Be it known that I, ALBERT BECK, a citizen of the United States, and a resident of Chicago, in the county of Cook and State of Illinois, have invented and produced a certain new and original Design for Game-Boards, of which the following is a specification, reference being had to the accompanying drawings, forming part thereof.

10 Figure 1 is a plan view of my invention. Fig. 2 is a transverse section therethrough, taken on the vertical plane indicated by dotted line 2 2, Fig. 1.

15 The leading feature of my design consists of a series of depressed grooves or channels inclosed and suitably arranged within a rectangular frame or wall.

20 In the drawings, A represents a rectangular board or card of suitable material, and B represents a thin strip of suitable material surrounding the same.

25 The top of the board is provided with a series of channels or grooves as follows: Commencing at each corner and extending diagonally toward the opposite corner a short distance are four short corresponding corner-channels *a a a a*. The inner open ends of each of these corner-channels terminate at the confluence of two corresponding segmental 30 channels *b b*, with which they communicate, said segmental channels curving in opposite

directions and ending at the mouth of the diagonally opposite corner-channel *a*. The segmental channels *b* connecting one pair of diagonally opposite alining corner-channels *a a* 35 cross the segmental channels connecting the alining corner-channels arranged at right angles thereto, and vice versa. As thus arranged, the segmental channels describe a quatrefoil, each of the four outer angles of 40 which terminate in a corner-channel, as shown. The area inclosed by the four segmental channels is intersected by two center channels *c c*, which are shown as straight and crossing each other at the center of the board, 45 one of said center channels being in alinement with one set of diagonally opposite corner-channels and the other of said center channels being at right angles thereto and in alinement with the other opposite corner-channels. 50

This board may be of any dimensions, and the channels therein should be deep enough to direct the movement of spherical bodies placed therein.

55 What I claim as new is—

The design for a "game-board" herein shown and described.

ALBERT BECK.
